UNITED STATES PATENT OFFICE.

CLAUD M. WALTZ, OF SUMMITVILLE, INDIANA.

BELT.

1,339,309.

Specification of Letters Patent.

Patented May 4, 1920.

Application filed July 20, 1918. Serial No. 245,946.

To all whom it may concern:

Be it known that I, CLAUD M. WALTZ, a citizen of the United States, residing at Summitville, in the county of Madison and State of Indiana, have invented new and useful Improvements in Belts, of which the following is a specification.

This invention relates to belts used as wearing apparel. The object of the invention is to produce what I term a quick detachable and adjustable belt, the same embodying means whereby the length of the belt may be adjusted from time to time, also means whereby the ends of the belt may be quickly connected and disconnected without disturbing the ordinary buckle and tongue with which belts are provided.

One of the principal advantages of the present invention resides in the invisibility of the connecting and disconnecting means, the belt, when worn by a person, resembling the ordinary buckle belt now in common use, the quick detachable means being entirely concealed even upon close inspection.

With the above and other objects in view, the invention consists in the construction, combination and arrangement of parts, as herein described, illustrated and claimed.

In the accompanying drawing:

Figure 1 is a fragmentary face view of the belt.

Fig. 2 is a rear elevation of the same.

Fig. 3 is a perspective view of the buckle and frame complete.

Fig. 4 is a perspective view of one end of the belt showing the metal tip with its eye.

Referring to the drawings, 1 designates a belt, such as is worn around the waist, such as an article of wearing apparel. The belt is shown as provided with the usual buckle engaging holes 2 to receive the tongue 3 of the buckle loop 4, said parts being of the ordinary construction and arrangement.

In carrying out the present invention, the opposite end of the belt is tapered as shown and covered by and inclosed within a metal tip 5, said tip being preferably riveted to the end of the body of the belt and being formed with a hole or eye 6 therethrough.

Extending from the inner cross bar of the buckle loop and pivotally connected thereto is a plate 7 having metal loops 8 through which one free end of the belt is inserted in the manner shown in Fig. 1, said loops 8 resembling the ordinary belt and retaining loops now in use. Extending from the back of the plate 7, is a hook 9 which is adapted for quick insertion through and removal from the eye in the tip 5. When the two ends of the belt are connected by means of said hook and eye, both the hook and eye lie behind the exposed end of the belt which has the holes to receive the tongue of the buckle. Therefore, the belt resembles in every respect, the ordinary belt now in use, but it has the advantage over the ordinary belt that the ends may be quickly connected and disconnected and the belt may also be adjusted in length from time to time as may be required. The tapered tip 5 enables the belt to be quickly and easily threaded through the loops or tunnels now provided on trousers in connection with which belts are to be used.

I claim:

1. A belt structure comprising a flexible member provided at one end with a series of holes and at its other end with an eyelet, in combination with a buckle structure including a plate having knuckles formed at one end and having formed adjacent its ends loops adapted to receive the belt, a buckle proper pivotally connected within said knuckles, and a hook secured on the rear face of said plate and adapted for engagement thereon of the eyelet. 75

2. In a belt structure, a body encircling flexible member provided in one end with an eyelet, in combination with a buckle detachably engaged with the other end of the flexible member and including a plate disposed rearwardly of the flexible member, and a hook secured upon the rear face of said plate substantially centrally thereof and engageable by said eyelet. 90

In testimony whereof I affix my signature.

CLAUD M. WALTZ.
